UNITED STATES PATENT OFFICE.

HENRY M. WEAVER, OF MANSFIELD, OHIO, ASSIGNOR TO THE BARR CASH AND PACKAGE CARRIER COMPANY, OF SAME PLACE.

CASH AND PACKAGE CARRIER.

SPECIFICATION forming part of Letters Patent No. 465,686, dated December 22, 1891.

Application filed March 18, 1891. Serial No. 385,524. (No model.)

To all whom it may concern:

Be it known that I, HENRY M. WEAVER, of Mansfield, in the county of Richland and State of Ohio, have invented certain new and useful Improvements in Cash and Package Carriers; and I do hereby declare the following to be a full, clear, and exact description of the invention, such as will enable others skilled in the art to which it appertains to make and use the same.

My invention relates to an improvement in propelling apparatus for cash and package carrying apparatus, the object being to afford novel means of attachment for the movable wire of apparatus of this character; and it consists in the usual double-track wires, in connection with the means for attaching these wires and spreading them, and in certain other novel features of construction and combination of parts, as will be hereinafter described, and pointed out in the claims.

In the accompanying drawings, Figure 1 is a view in side elevation of a portion of the apparatus, showing the novel features. Figs. 2 and 3 are details, and Fig. 4 is a section on line xx of Fig. 3.

B represents a hanger depending from the ceiling or other support in the usual manner. To the lower end of this hanger is attached a casting A. The lower part of the latter is preferably flat and of sufficient thickness to receive a pulley D between its walls or sides. Integral with the casting and extending rearwardly therefrom is an arm C. A pair of flat bars F F are pivotally supported at their rear ends f on the arm C and pass on either side of the casting A. The track-wires K K' are connected, respectively, to the bars F F and the lower end of the casting A, as shown, the former connection being yielding and the latter rigid.

As the peculiar connection with the bars F F constitutes the essential feature of my invention, I will proceed to describe it in detail. A rod or block H is pivoted in the free ends of the bars F F, as shown in Fig. 3. Rod J passes loosely through a hole in this block, thus permitting a free sliding movement. Spiral spring P is mounted on this bolt, bearing at one end against the block H and at the other against a nut L. The latter is adapted to be screwed on or off of the rod for different distances to regulate and vary the tension of the spring. The track-wire K is at-

tached to the outer end of the rod P. Cord 55 N is connected at point M to the bars F F and passed over pulley D, its free end extending down within easy reach of the operator, where it is furnished with a handle O. By drawing down on this handle the free 60 ends of the bars F F are elevated, and the wires are thus spread apart back of the wheels of the carrier Q, whereby the latter is propelled. As the swivel H rises spring P is compressed and the swiveled block H turns, allowing the rod J to maintain the position assumed by the track-wire K attached to it. The spring allows of the retreating motion of the bars at their free ends, assists the return to their normal positions, and keeps the 70 wires taut.

It is evident that slight changes might be resorted to in the form and arrangement of the several parts described without departing from the spirit and scope of my invention, and hence I do not wish to limit myself to the exact construction herein set forth; but,

Having fully described my invention, what I claim as new, and desire to secure by Letters 8c Patent, is—

1. The combination, with a fixed and movable support and track-wires connected with said support, of a block pivoted in the movable support and means for yieldingly connecting one of the track-wires with the pivoted block, substantially as set forth.

2. The combination, with a fixed support and a track-wire secured thereto, of a support hinged at one end to the fixed support, 90 a block pivoted in the free end of this support, and a track-wire having a yielding slideable connection with the block, substantially as set forth.

3. The combination of a hanger, a track-wire secured thereto, bars pivotally connected to the hanger, a block pivoted in the free ends of the bars, a bolt passing loosely through the block, a spring on the bolt, and a track-wire connected to the bolt, substantially as set 100 forth.

In testimony whereof I have signed this specification in the presence of two subscribing witnesses.

HENRY M. WEAVER.
